FINGER RING

Bernard I. Mechanic, 2425 Oakton St.,
Evanston, Ill. 60202

Filed Feb. 28, 1972, Ser. No. 230,216

Term of patent 14 years

Int. Cl. D11—01

U.S. Cl. D45—10 A

FIG.1

FIG.2

FIG.3

FIG.4

FIG. 1 is a top plan view of a finger ring showing my new design;

FIG. 2 is a bottom plan view thereof;

FIG. 3 is a front elevational view, the rear elevational view being substantially identical; and

FIG. 4 is a right side elevational view; the left side elevational view being substantially identical.

I claim:

The ornamental design for a finger ring, as shown and described.
